Primary Examiner — Ruth McInroy(74) *Attorney, Agent, or Firm* — Themis Law(57) **CLAIM**

The ornamental design for a cleaning attachment, as shown and described.

DESCRIPTION

FIG. 1 is a top perspective view of a cleaning attachment showing our new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a right side perspective view thereof in an example of use, with a floor contacting member attached thereto; and, FIG. 10 is a bottom perspective and exploded view thereof as in the example of use shown in FIG. 9.

The elements shown in broken lines are for illustrative purposes only and form no part of the claimed design.
